(57) **CLAIM**

I claim the ornamental design for a shock tower for a model vehicle, as shown and described.

DESCRIPTION

FIG. 1 is a top, right, front perspective view of a shock tower for a model vehicle;

FIG. 2 is a top, left, rear perspective view thereof;

FIG. 3 is a right elevation view thereof;

FIG. 4 is a left elevation view thereof;

FIG. 5 is a rear elevation view thereof;

FIG. 6 is a front plan view thereof;

FIG. 7 is a top plan view thereof;

FIG. 8 is a bottom plan view thereof; and,

FIG. 9 is a top, front, left perspective environmental view of four shock towers for a model vehicle mounted on a model vehicle platform.

In the drawings, the broken lines depict environmental subject matter only and form no part of the claimed design. Whereas the broken line showing of the model vehicle platform is provided for the purpose of illustrating environmental subject matter only and forms no part of the claimed design. In addition, in FIG. 9, four shock towers for a model vehicle are shown mounted on the model vehicle platform but only a single shock tower for a model vehicle is claimed.
